UNITED STATES PATENT OFFICE

JOHN W. PHILLIPS, OF EAST ORANGE, NEW JERSEY

ROLLER RULER

Application filed June 5, 1928. Serial No. 283,039.

The present invention relates to a ruling instrument, and, in the present form, to a roller type of ruler.

An object of the invention is to provide an instrument by means of which a line may be drawn, painted, cut or otherwise made contiguous to another line, such as an edge of a molding or piece of furniture, and at variable distances therefrom even when the guiding line or edge is curved.

For this purpose the invention, in the preferred form shown herein by way of example, consists of a relatively flat instrument provided with supporting and guiding rollers, the instrument being extensible and being provided with guide rests for pencils, paint brushes, or cutting or marking implements, and being preferably provided with length indications or ruler graduations. A preferred embodiment of the invention is illustrated in the accompanying drawings, in which:

Fig. 1 is a perspective view of a preferred form of the invention and illustrates one application of the instrument in practice;

Fig. 2 is a longitudinal vertical section through the device of Fig. 1;

Fig. 3 is a transverse sectional view on the line 3—3 of Fig. 1;

Fig. 4 is a detail perspective view of one of the sliding guide clips;

Fig. 5 is a perspective view of a modified form of the invention;

Fig. 6 is a perspective view of another modified form of the invention and of a different application of its use;

Fig. 7 is a vertical transverse sectional view taken on the line 7—7 of Fig. 5;

Fig. 8 is a vertical transverse sectional view taken on the line 8—8 of Fig. 6.

Referring in detail to the drawings and particularly to Figs. 1 to 4 inclusive, the embodiment of the invention here illustrated comprises two interengaging relatively extensible sections 11 and 12 relatively mova-

ble longitudinally and secured together for sliding extensible movement by a pair of guiding clips 14 and 15. Clip 14 has a vertical central portion secured to the end of the section 12 and is provided with a top and bottom flange, the flanges being of greater length than the central section which fits within the central cut-out portion 18, and the flanges overlying the upper and lower faces of the parallel arms 19 and 20 of the member 11. The clip 14 is thus fixed with respect to the section 12 and has no movement relative thereto.

Clip 15, similar in construction to the clip 14, fits between the parallel arms 19 and 20 and has its upper and lower flanges secured to said arms, so that the clip 15 is fixed to the section 11 and is movable with said section with respect to the cooperating section 12. The construction described permits relative longitudinal extension of the two sections with respect to each other and insures that any relative movement between them will be absolutely rectilinear.

The section 11 is provided with a supporting roller 24 and with a pair of guide rest arms 27 and 28 which serve as guide rests for a paint brush, pencil or other marker, and for convenience the section 11 and one or both of the guide rest arms may be provided with circular or other openings 30 therethrough for the purpose of rigidly holding a pencil or other marker. A projection 50 on the arm 27 extends parallel to a projection 51 on the arm 28 to form a right-angled guide rest to aid the user in holding the marking instrument steady with respect to the ruler.

The section 12 is provided with a supporting roller 34 similar to the roller 24 and is likewise provided with a pair of arms 37 and 38. Each of these arms is provided with a guide roller 39 rotatable on an axis at right angles to the axis of the supporting rollers 24 and 34. The guide rollers maintain easy

and absolutely rectilinear movement of the ruler as a whole in the direction of the edge 40 when the ruler is in use. The section 12 and its arms 37 and 38 may also be provided with openings 30 to serve as pencil or other guides.

Referring to Fig. 5, the sections 111 and 112 correspond to the sections 11 and 12 of Fig. 1; supporting rollers 124 and 134 are provided as before, as are also a pair of guide rollers 139. The guide arms are omitted in this modification, however, and the clips 114 and 115 pass about the outside of the two sections, the clip 114 being secured to the section 112, and the clip 115 secured to the section 111. The arms 116 and 117 of the section 111 cooperating with the arms 119 and 120 of the section 112 are provided on their inner edges with a series of guide rests herein shown as being in the form of small wire loops 121. These serve the purpose of holding in fixed position with respect to the ruler, a pencil, paint brush or other marking instrument. A straight edge guiding rest 123 is provided at the end of the section 111 and is provided with two parallel end arms 150 and 151 which cooperate with the guide portion 123 to form at each end thereof a right-angled guide rest.

Referring to Fig. 6, the embodiment of the invention here shown is particularly well adapted for relatively greatly curved edges parallel to which it is desired to draw or paint a line. In this form the ruler 212 is provided with a pair of spaced-apart supporting rollers 224 and 234. The ruler is provided along its edges on both faces with appropriate graduations, and at one of its ends is provided with a guide rest 223 similar to the guide rest 123 of Fig. 5, and is also provided with a pair of short parallel extensions 250 and 251 to cooperate with the guide rest. The other end of the ruler is provided with an extension 260 at the end of which is carried a single guiding roller 239. The marker may be rested upon the guide rest 223 or simply along the graduated edge of the ruler at the desired distance from the edge 240.

From the foregoing description it will be seen that the invention provides an extensible guide ruler by means of which decorative or constructional lines may be drawn, cut, painted or otherwise marked parallel to straight or curved edges; and that the invention provides a small antifrictionally supported instrument for this purpose with guiding means enabling it to follow a base or reference edge of any curvature. Various modifications may be made in the construction of the invention without departing therefrom, as defined by the following claim.

What is claimed is:

A guiding ruler of the character described consisting of two longitudinally adjustable

telescoping sections, each section being provided with a supporting roller adapted to support the sections parallel to a plane surface, one of said sections having a marking implement rest formed therein, and the other of said sections having depending contact rollers mounted at the end thereof and at right angles to said supporting rollers for guiding the ruler along a reference edge.

In testimony whereof I affix my signature. 75
JOHN W. PHILLIPS.
